HYDRAULIC PRESS

Richard W. Dinzl, Narberth, Pa., assignor to Baldwin-Southwark Corporation, a corporation of Delaware

Application October 4, 1935, Serial No. 43,605

3 Claims. (Cl. 100—50)

This invention relates generally to hydraulic presses and more particularly to a hot plate press. It is an object of my invention to provide a press in which the elements are so combined that the press is not only relatively simple, compact and sturdy but is also economical in construction, maintenance and operation. A further object is to provide an improved combination whereby the various parts are readily accessible notwithstanding the compact arrangement of the press. A further object is to provide an improved combination of press elements whereby they structurally and functionally cooperate to permit certain elements to perform a multiplicity of functions and thereby minimize the cost of the apparatus as well as rendering it compact. A still further object in this respect is to provide a compact unit through which air is circulated for cooling purposes by an improved and simplified air circulating combination.

Other objects and advantages will be more apparent to those skilled in the art from the following description of the accompanying drawings in which:

Fig. 1 is a vertical sectional view taken on the line 1—1 of Fig. 2;
 Fig. 2 is a transverse section taken on the line 2—2 of Fig. 1;
 Fig. 3 is a horizontal section taken on the line 3—3 of Fig. 1;
 Fig. 4 is a horizontal section taken on the line 4—4 of Fig. 1;
 Fig. 5 is an enlarged elevational view showing the construction of the rams.

In the particular embodiment of the invention which is disclosed herein merely for the purpose of illustrating one specific form among possible others that the invention might take in practice, I have shown in Fig. 1 a pair of side frame members 1 and 2, these members being preferably flat slab steel extending for the full height of the machine and defining substantially the full width thereof as indicated by their vertical edges 3—3, Fig. 2. The side plates are supported upon a plate metal base 4 and held in spaced relation by vertical and horizontal plate metal members 5 and 6 all of which are welded together whereby a pump sump 7 has its bottom formed by base plate 4 and its end walls by the side frame members. A cast cylinder block generally indicated at 8 is provided at each of its ends, Fig. 4, with a recess 9, thereby forming a pair of arms on which are formed lateral projections or keys 10 disposed within suitable transverse keyways 11 in the inner faces of the frame sides 1 and 2. The cylinder

casting and frame sides are secured together in any suitable manner such as by bolts. Supported between and by the upper ends of side members 1 and 2 is a stationary platen 13 having transverse keys 14 seated within keyways 15 in the inner faces 5 of the side members.

Cylinder block 8 has a pair of cylinders in which rams 17 and 18 are disposed, it being noted that the lower cylinder heads 19 of each cylinder are cast integrally with the cylinder walls. A movable platen 20 rests upon the upper ends of the rams and is guided by the frame sides. Inasmuch as the guiding structure is the same at each end of platen 20, only one end thereof will be described. As shown in Fig. 3, a vertical guide block 22 is secured to or formed on the end of platen 20 and projects as shown in Fig. 1 a substantial distance below the bottom thereof as generally indicated at 23. Any suitable lateral brace 24 is provided to support the depending portion of the 20 guide. This guide has a groove 21 preferably tapered as shown in Fig. 3 to ride upon a complementary shaped vertical guideway 25. Guideway 25 is secured to the inner face of the frame side member by a bolt 26, although a series of screws 27 are provided to adjust the guideway 25 inwardly or outwardly. After any adjustment has been made, bolt 26 is tightened. The guides and guideways are preferably of the substantial length 30 as described, and in order to accomplish this in a very compact machine, I provide the openings 9 in the cylinder casting and extend the guide and guideways downwardly into this space, all without sacrificing any sturdiness of the press which characteristic is of particular value in a press of the 35 type herein disclosed.

To accomplish additional compactness combined with simplicity and sturdiness, and also minimum cost of manufacture and maintenance, I have formed a control valve directly in the 40 lower portion of the cast cylinder block. As shown in Fig. 1, side plate 1 has a hole 27 to loosely receive a packing boss 28 extending laterally from the cylinder casting 8. An axially movable valve 29 is adapted to engage a valve 45 seat 30, and a suitable packing gland construction is secured to the side plate 1, thereby providing not only a highly compact arrangement but one that is entirely rigid and not likely to become damaged or get out of alignment. Valve 29 can be operated by any suitable hand lever 32. If desired, a finer degree of adjustment can be obtained by an auxiliary valve 33 operated by a hand wheel 34 to control auxiliary ports 35. The two valves are thereby arranged to control

flow of fluid from a supply passage 36 through the horizontal cylinder passage 37 as by bypassing fluid therefrom to return pipe 37a.

In order to further obtain as high a degree of compactness as possible, I have placed a pump 40 and its motor 41 directly beneath the cylinder block and utilize a base 42 of the motor pump unit as a cover for sump 7. As a result of this arrangement, the discharge pipe 43 of the pump 10 may be connected to pipe 36 with minimum connections.

In order to effectively dissipate heat that might be transmitted from the hot plates 44 and 45 to the cylinder block and pumping mechanism, I 15 circulate air around the cylinders and pump. To accomplish this efficiently in a simple and compact manner, I utilize side plate 2 not only as a support for a motor fan unit 46 but also as one wall of an internal air chamber and also form 20 an air inlet opening 47 in the side plate. A sheet metal panel 48, Fig. 2, is secured to and extends entirely between the rear edges of side plates 1 and 2 and also extends from base plate 4 to the uppermost edge of the cylinder block 8. A front 25 sheet metal panel 49 is similarly secured to the front edges of side plates 1 and 2, although this front panel has a series of louvered discharge openings 50. Air is circulated by fan 46 through opening 47 and around the motor-pump unit 30 and then upwardly and outwardly through the openings 50 which extend for the full width of panel 3, it being noted in Fig. 2 that the openings are adjacent the front portion of pockets 50a in the cylinder casting. These pockets extend 35 entirely around and between the cylinders and communicate with the end openings 9 thereby providing a complete air circulating passage through the cylinder block. Also, air will flow vertically through the cylinder block end openings 9, thus preventing excessive heating of the 40 guide and guideways and thence discharge to the atmosphere around the underside of the movable platen 20. As a result of this improved cooling system, the guide and guideways require minimum clearance which is conducive to a higher 45 degree of accuracy and also it is easier to maintain a proper film of lubricant on the guiding surfaces.

To accomplish the foregoing described high degree of compactness of the press without, however, sacrificing the accessibility of the working parts for purposes of repair or inspection, I have so constructed and arranged the rams and the surrounding press structure that the rams may 50 be conveniently removed without dismantling the press. When the rams are moved upwardly so that hot plates 44 and 45 are in contact, rams 17 and 18 are still within their cylinders in complete operative relation thereto. In order to remove the rams, the operator would first bring the platens 44 and 45 into contact and place a block 55 of wood or other suitable material between the cylinder casting 8 and the underside of platen 20, and then an upper ram section 51, Fig. 5, 60 would be laterally removed followed by removal of a second ram section 52. The upper ram section is secured to platen 20 by bolts 53, while bolts 54 secure the two ram sections together. As is shown more clearly in connection with one 65 of the diametrically opposed bolts 54, a recess 55 is formed in the sides of the rams. A lateral slot 56 connects the recess with the bottom surface of the upper section. The recess is also of sufficient height that the bolt may be unscrewed from 70 lower section 52 and laterally removed through

slot 56. A similar construction is employed for the bolts 53. Hence upon removal of the bolts 53 and 54, the upper ram section 51 may be laterally removed and thereafter the lower ram section may be raised and laterally removed. To assist the removal of the lower ram section as well as its insertion, the cylinder is preferably cut away at 57. Hence the ram packing 58 may be inspected or replaced without the necessity of either dismantling the platen 20 from its guides 10 or of removing any portion of the press structure or piping connections to the ram cylinder.

From the disclosure it is seen that I have provided a press construction whose component parts cooperate both structurally and functionally in such a manner as to insure maximum compactness combined with sturdiness, accuracy and simplicity of operation, all at a minimum cost of manufacture, maintenance and operation.

I claim:

1. A hydraulic press comprising, in combination, a base, a pair of slab side frame members extending continuously from said base to the top of said press, a stationary platen rigidly secured to the upper end portion of said side members, a cast cylinder block of substantial height and substantially equal to the width of said side members and having vertically extending end openings interposed between the front and back edges of said block immediately adjacent said side frame members thereby providing U-shaped end portions on the cylinder block for engagement with the side frame members, means for rigidly securing said cylinder block to said side members at a vertically intermediate point thereof, a cylinder 30 formed in said block and having a lower cylinder head, a ram in said cylinder, a movable platen supported on said ram and located beneath said stationary platen, guide means carried by said movable platen adjacent said side frame members and adapted to project downwardly into said vertical end openings of the cylinder block, and guide elements associated with the inner faces of said side frame members for cooperation with said guide means.

2. A hydraulic hot plate press comprising, in combination, relatively wide flat side members, a stationary upper platen supported thereby, a cylinder block substantially equal to the depth of said side members and supported thereby at 50 an intermediate portion thereof below said stationary platen and having vertically extending end openings adjacent said members, a cylinder formed in said block, a ram in said cylinder, a platen supported by said ram beneath said stationary platen, hot plates supported on said platens, a motor-pump unit disposed between said side members beneath said cylinder block for supplying operating fluid to said cylinder, and means for circulating air around said motor-pump unit 55 and through said end openings to cool said motor and minimize transfer of heat from the hot plate to the cylinder and ram elements, said circulating means including an air opening in one of said side members adjacent said motor-pump unit and a motor fan unit supported by said latter frame member adjacent said air opening.

3. A hydraulic press comprising, in combination, a base, a pair of slab side frame members extending continuously from said base to the top 70 of said press, a stationary platen rigidly secured to the upper end portion of said side members, a cast cylinder block of substantial height and substantially equal to the width of said side members and having vertically extending recesses 75

5 cated immediately adjacent said side frame members and disposed between vertical planes containing the front and back edges of said block whereby the remaining end portions of the cylinder block are for engagement with the side frame members, means for rigidly securing said cylinder block to said side members at a vertically intermediate point thereof, a cylinder formed in said block and having a lower cylinder head, a ram in

said cylinder, a movable platen supported on said ram and located beneath said stationary platen, guide means carried by said movable platen adjacent said side frame members and adapted to project downwardly into said vertical end recesses of the cylinder block, and guide elements associated with the inner faces of said side frame members for cooperation with said guide means.

5
